UNITED STATES PATENT OFFICE.

FRITZ SCHROETER, OF BERLIN, GERMANY, ASSIGNOR TO GESELLSCHAFT FUR DRAHTLOSE TELEGRAPHIE M. B. H., OF BERLIN, GERMANY, A CORPORATION OF GERMANY.

METHOD AND ARRANGEMENT FOR THE PRODUCTION OF STEREOACOUSTIC PHOTO FILMS.

Application filed June 5, 1926, Serial No. 113,890, and in Germany June 22, 1925.

The object of my invention is to use the so-called stereo-acoustic (plastic) audition in connection with phono-films. It is known that plastic audition ("binaural audibility") of acoustic productions or pieces is obtained for the reason that the low frequency phenomena are made perceptible to both ears with a time difference, this difference being governed by the phase angle with-
5 in which the sound source is localized by the auditory senses. According to my invention it is possible to obtain such stereo-acoustic audition in the reproduction of sound phenomena with the use of phono-films as inter-
10 mediary means.

The invention, more particularly speaking, consists in the double photographic recording of the sound waves upon the film, whereby the acoustic phenomena are recorded 20 twice. The invention can be carried into practice, for example, by recording the two low frequency phenomena in synchronism, by the co-action of which binaural or plastic audition is produced. In this recording, 25 each record or illumination device which causes such a record is coordinated to a separate microphone, or a separate group of microphones. Each microphone is so mounted and secured at the proper relative 30 position that it may be caused to act with the proper time difference upon the controlling luminous sources provided for making the record of the sound waves.

It can thus be seen that the position of the 35 two microphones in relation to the sounds detected corresponds to the position of the ears of a human being, so that the sound reception may be similar to that reception obtained by a person positioned at the point.

40 In the reproduction of the sound, by my invention I also use a dual system, for example, two photo-electric cells which are each influenced by the phono-film produced in the recording process. By means of amplifiers the photo-electric cells are brought 45 to act upon loud speakers mounted at appropriate points in the room, or else upon head sets, in such a manner that one of the telephone receivers is influenced by the action 50 of the first photo-electric cell, and the other receiver influenced by the second photo-electric cell.

Other objects of my invention are to produce an arrangement for producing binaural

audition in which there is a relatively simple 55 construction and arrangement of parts, efficient operation, and a relatively small installation expense.

Still other objects will be apparent from the following description and claims when 60 read in connection with the accompanying drawing, showing greatly simplified diagrams of my arrangement, wherein:

Fig. 1 shows, by way of example, an equipment for making the records; and

Fig. 2 shows an example of a means for reproducing the acoustic phenomena.

Referring first to the production of the records, as illustrated by Fig. 1, two microphones 1 and 2, each fed from a common energy source 3 are placed at different relationship to the sound source (which may be assumed to be at a point S) in accordance with the requirements of stereo-acoustic audition. The oscillations produced in the microphones 70 1 and 2 by the incoming sound impulses are carried through transformers 4 and 5, respectively, to amplifiers 6 and 7 where the potential is raised. The raised potential is then carried to the Kerr cells 8 and 9 where 75 it is used to control the voltage on the plates of the said cell.

The voltage control on the plates of the Kerr cells, in conjunction with the corresponding optical polarization means, well 80 known in connection with this type of cell, consisting of a condensing lens 10^a to direct the light rays from the luminous sources 10 and 11 to a Nicol prism 11^a where it is polarized or in other words, the light entering 85 in one direction is eliminated and the remaining light acts as if it were in a plane at right angles to the first direction, and directed to the Kerr cell. It is well known that a light ray when polarized may be divided up into a horizontal and a vertical component, and when this light passes between the plates of the Kerr cell the vertical component of the light is either speeded up 90 or slowed down with respect to the horizontal component, depending upon whether the plate voltage on the cell is either increased or decreased.

The resultant component of the vertical and horizontal wave is thus changed into a 95 different plane of polarization, and this is made evident when passing through the analyzing Nicol prism set at right angles to

the first for were the plane not changed, all the light would be blocked out as the second Nicol has the same property as the first of eliminating all light active in one direction. 5 The increase or decrease of voltage is, of course, dependent upon the energy supplied in the microphone and amplified by the amplifiers 6 or 7. Since the microphones are usually not in the same relative position to 10 the sound source, a slightly different effect will be produced in each cell at the instantaneous time, for the same effect can only be produced when the sound impulses in each microphone are exactly in the same angular 15 phase relationship. As above stated, the polarized light coming to the cell from the light source is weakened to a greater or lesser extent at the rhythm of the oscillations of speech or other sound which is to be 20 transmitted.

In the path of the rays passing through the Kerr cell and the second Nicol prism 11^b, I place a lens 10^b to direct the light ray to a film 14 comprising a pair of phono-film 25 bands 15 and 16, band 15 being coordinated to microphone 1 and Kerr cell 8 and band 9 coordinated to microphone 2 and Kerr cell 9. The ray pencils 12 and 13 produce upon the bands 15 and 16 of the film 14 lighter or 30 darker images of the slit of the respective Kerr cells depending upon the voltage strength on the plates of the said cells. The oscillations are thus recorded in synchronism, but displaced with reference to time, 35 in conformity with the actions upon the two microphones, as above stated.

In reproducing, as shown by Fig. 2, two light sources 17 and 18, in combination with suitable optical auxiliaries, as lenses 19 and 40 20, project slit-like images through the bands 15 and 16 of the film 14 upon the photo-electric cells 21 and 22. The photo-electric cells 21 and 22 are supplied with energy from a joint battery 23, and the variations 45 in current occasioned by brighter and darker stripes or bands on the film are fed to the amplifier tubes 25 and 26. From this point the current is amplified and brought to receivers 27 and 28, which, similar to the 50 microphones 1 and 2, are disposed and connected in conformity with the requirements of plastic sound reproduction. By this means the travelling film produces a corresponding audition or auditory perception to 55 that of the microphones.

The optical path of the rays is shown with certain diagrammatic simplification, for the true proportions have been left out of consideration in order to simplify the illustration and to make it more readily understood. 60

If desired, the plastic properties in the reproduction can be further improved by the use of additional microphones, the latter being placed at the proper points with relation to the others, and the recording of a 65

corresponding number of additional phono-film bands on the film strip which are co-ordinated to a correspondingly larger number of reproducing apparatus. The form in which the acoustic phenomena are recorded and marked upon the film, and the light controlling means used therefor are immaterial, so far as the fundamental features of this invention are concerned. It is advantageous, however, to operate with means of this kind being as free from sluggishness and working as quantitatively as possible, for instance, by having recourse to the Kerr effect (electric double refraction in a condenser filled with a suitable medium for example nitro-benzol), in order that the higher frequencies, especially in the case of music, may not be impaired. 70 75 80 85

The idea of the Kerr effect, per se, is old and has been explained in greater detail in each of the following publications, "Theory of Light"—Preston—1912, page 445 and following, and in vol. 1 of the "Philosophical Magazine"—pages 337 to 446.

While I have herein shown and described only one form of my invention, other modifications may be made without departing from the spirit and scope of the invention as defined by the appended claims.

Having described my invention, I claim: 95

1. A binaural system for recording sound which includes, a plurality of spaced sound pick-up devices, an amplifying means associated with each of said sound pick-up devices, electrostatic means connected with each of said amplifiers and receiving potentials from said amplifiers in accordance with the intensity of sound reaching the amplifier, a light source associated with each of said electrostatic devices, means for polarizing the light from said source and directing the same through said electrostatic devices, and means controlled by the potentials applied to said electrostatic devices for doubly refracting said plane polarized light beam in accordance with the sound received at each of said sound pick-up devices, and a light sensitive film for recording the light passing through said electrostatic device. 100 105 110

2. The system claimed in claim 1 comprising in addition, means for reproducing the sound thus recorded on said light sensitive film including, a pair of photo cells subject to light intensities varied in accordance with the record on said film, and a pair of sound reproducers controlled from said photo cells for reproducing the sound effects heard at the said sound pick-up device and producing binaural effects upon the ears of a listener at the point of reproduction. 115 120

3. A system for producing binaural effects upon a light record which includes, means provided at points separated a distance from each other so as to receive sound impulses both in phase with each other and slightly 125 130

out of phase with each other depending upon the location of the sound source for receiving sound impulses and detecting a phase and time difference in the sound waves 5 thus received, an amplifying means independently associated with each of said sound pick-up devices, a Kerr cell connected with each of said amplifiers, a light source associated with each of said Kerr cells, means 10 for polarizing the light from said source and directing the same between the plates of said Kerr cell, and means provided by said Kerr cell and governed in accordance with the potentials produced upon said Kerr cell from said amplifier for controlling the said 15 polarized light beam passing therethrough in accordance with the sound waves impressed upon said sound pick-up device, and a light sensitive recording strip associated with said Kerr cells for producing thereon a 20 double record of the sound received wherein each record differs from the other at a fixed and predetermined point by a phase difference similar to the phase difference of the sound received at the said sound pick-up 25 device.

FRITZ SCHROETER.
